INVENTOR.
JAMES S. JOHNSTON
MILLARD L. JOHNSTON
BY *Thomas L. Wilder*
ATTORNEY.

UNITED STATES PATENT OFFICE.

JAMES S. JOHNSTON AND MILLARD L. JOHNSTON, OF UTICA, NEW YORK.

AEROPLANE.

Application filed January 28, 1918. Serial No. 214,201.

To all whom it may concern:

Be it known that we, JAMES S. JOHNSTON and MILLARD L. JOHNSTON, citizens of the United States, residing at Utica, in the 5 county of Oneida and State of New York, have invented certain new and useful Improvements in Aeroplanes, of which the following is a specification, reference being had therein to the accompanying drawing.

10 Our invention relates to an aeroplane and we declare the following to be a full, clear, concise, and exact description thereof sufficient to enable anyone skilled in the art to which it appertains to make and use the 15 same, reference being had to the accompanying drawings in which like reference characters refer to like parts throughout the specification.

The object of the invention is to provide 20 an aeroplane that has an efficient and simple mechanism for the control of the movements of the plane while in the air. To this end the aeroplane is equipped with a rudder that is adapted to be turned about on a 25 horizontal axis by the manipulation of a handle and to be swung at an angle by the actuation of a pedal, whereby to govern the direction of travel of the aeroplane.

The object will be understood by refer- 30 ring to the drawings in which:

Fig. 1 is a perspective view of the aeroplane;

Fig. 2 is an enlarged sectional view of a gear and indicator employed;

Fig. 3 is a detail perspective view of a 35 partition used;

Fig. 4 is a detail perspective view of an end member of a rock frame employed;

Fig. 5 is a detail perspective view of a 40 pendulum member employed;

Fig. 6 is a detail perspective view of a pedal and supporting member employed;

Fig. 7 is a vertical section of the aeroplane;

Fig. 8 is a detail perspective view of the 45 rudder plane and immediate parts used;

Fig. 9 is a detail perspective view of a seat and holding bracket employed;

Fig. 10, is an enlarged detail view of a 50 rock frame used;

Fig. 11 is a fragmentary view of the aeroplane, showing a vertical section of a modification thereof;

Fig. 12 is a fragmentary view showing a 55 horizontal section of the aeroplane and look-

ing down from above upon the planes which are actuated in a modified manner;

Fig. 13 is a fragmentary view, showing a vertical section of the modified construc- 60 tion illustrated in Fig. 12.

Referring more particularly to the drawings, the body or casing of the aeroplane is represented by —1— and is equipped with four blades 2—2—2—2 adapted to give stability to the aeroplane while in the air. An 65 opening 3 is made in the forward part of the casing —1— to admit the pilot to his seat 4, which is suspended by the brackets 5 that are sleeved to the bars 7 of the rock frame 8. The rock frame 8 comprises the bars 7 70 and end members 9 and 10. The end member 9 has an orifice 11 which bears upon the end of the tube 12. A spur gear 13 is formed integral with the tube 12 and meshes with a spur gear 14 fixed to turn with the shaft 15 that has bearings at either end in the members 9 and 10. A spur gear 16 is mounted to turn with the opposite end of the shaft 15 and meshes with a spur gear 17. The gears 14, 16 and 17 are all of equal 75 diameter. The gear 17 is made integral with a shaft 18 that has a crank handle 19, whereby to revolve said gear and shaft within the collar 20 that projects through an opening in the end member 10 and held 80 thereto by the nut 21 mounted upon the threaded end of the collar 20. A key 22 between the contiguous edge of the end member 10 and the collar 20 prevents said collar from turning with the shaft 18. The outer 85 face 23 of the collar 20 is cut with short fissures 24 disposed at each quarter turn of the face 23 and designated "Up," "Right," "Down" and "Left," whereby to indicate the direction of travel of the aeroplane to 90 which the steering mechanism is set. A tooth 25 integral with the crank handle 19 is adapted to fit into the fissures 24, when the crank handle 19 is turned, whereby to indicate the proper degree of turning of 95 the handle 19 to secure the desired direction of the aeroplane. A spring 26 disposed about the shaft 18, permits the tooth 25 to move in and out of the fissures 24.

The turning of the handle 19 will actuate the train of gears 17, 16, 14 and 13 which latter gear is integral with the tube 12. A cap or member 30 is fixed to revolve with the opposite end of the tube 12. The cap 30 is recessed at 31 for the projection of a 100 105 110

link 32 that is pivoted at one end to the shaft 33 and at the other to the bracket 34 that is riveted to the rudder plane 35. The bracket 34 is fulcrumed to the flanges 36 of 5 the cap 30 at 37.

The tube 12 has bearings in the boss 38 attached to the casing —1— and in the boss 39 attached to the partition 40 that has an enlarged perimeter 41. Screws or bolts 10 42 are used to hold the partition 40 in place with respect to the casing —1—. The shaft 33, disposed inside of the tube 12, is reduced at 43 and surrounded with a coiled spring 44 that bears at one end against the 15 shoulder of the shaft 33 and at the other against the shoulder 45 formed in the tube 12, whereby to push the shaft 33 normally outward. A collar 46 is fixed to the free end of the shaft 33. The upper ends 20 47—47 of a member 48, which ends straddle the shaft 33, bear against the inner surface of the collar 46. The lower ends 49—49 of the member 48, which ends straddle the shaft 15 are curved upward to form 25 bearings about a bracket 50 fixed to the end member 9 of the rock frame 8. One of said ends 49 is extended to provide a pedal 51. The bracket 50 acts as a fulcrum for the member 48, whereby the pressure downward of the foot upon the pedal 51 will rock the member 48 and cause the upper ends 30 47 to draw the shaft 33 forward against the tension of the coiled spring 44. This movement of the shaft 33 outward will 35 draw the rudder plane 35 into the position indicated by the dotted lines in Fig. 1. The outer edges of the flanges 36 of the cap 30 are beveled at 52 to allow for the actuation of the rudder 35 to the dotted line 40 position illustrated in Fig. 1.

The bars 7 of the rock frame 8 are extended through and into the pendulum member 53 which has a lug 54 that projects into an arc shaped recess 56 made in 45 the forward partition 55 equipped with an enlarged perimeter. Bolts 42 are used to hold the partition 55 in place.

The mechanism for moving the aeroplane through the air embodies the propeller 50 blades 60 which are formed integral with the hub 61 that is threaded to the forward end of the hollow tube 62. The tube 62 has loose bearings in the boss 63 secured to the casing —1— and in the forward partition 55. A gear wheel 65 is attached to the rear end of the tube 12 and is connected by a sprocket chain 66 with the gear wheel 67 of the engine 68 housed in the casing 69 attached to the frame —1— of the aeroplane.

The upper plane 70 is held by a frame work 71 that is secured to the casing —1—. The aperture in the plane 70 for the entrance and exit of the pilot to the interior 60 of the aeroplane is normally closed by the

hinged doors 72—72. The doors 72 are provided each with a recess 73, for the insertion of the hand of the pilot, whereby to throw open the same for admission. The lower plane 80 has a central recess for the projection of the engine casing 69. Stay rods 75 are used to strengthen the planes 70, 80.

A machine gun 81 is disposed within the hollow tube 62. The forward end of the machine gun 81 is supported in the boss 82 that fits loosely within the tube 62. The stock end of the machine gun 81 rests in a recess 83 made in the end member 10 of the rock frame 8, whereby the machine gun 80 81 will revolve with the frame 8 to thereby always remain in a level position relative to the earth and irrespective of the aeroplane. A loose collar may be mounted to turn in the recess 83 and the stock mounted 85 in the collar, whereby the gun 81 could be held in a level position, when the rock frame 8 is locked to the casing —1— of the aeroplane, if it should be found desirable to so lock the rock frame 8. In the 90 event of the use of the loose collar, a gravity weight would be attached to the gun to keep the same level.

The front sight 85 of the gun is plainly visible through the rear sight 86, although 95 the rapidly moving propeller blades 60 intervene.

In order to guide the direction of the aeroplane while it is in the air, the aviator will manipulate the crank handle 19. If he 100 wishes to go upward, the aviator will turn the handle 19 until the tooth 25 thereof is opposite the fissure 24 mark "up" on the face or dial 23 and then push downward with his foot upon the pedal 51. The actuation of the handle 19 will revolve the train of gears 17, 16, 14 and 13 and effect a rotation of the tube 12 and rudder 35 into a horizontal position, and the actuation of the pedal 51 will rock the member 48, whereby to draw the shaft 33 forward against the tension of the coiled spring 44, to turn the rudder 35 upon its fulcrum 37, so that the rudder will be inclined at an angle upward. This position of the rudder 35 will 115 effect an upward movement of the aeroplane. Likewise, the rudder 35 can be turned at any angle on its horizontal axis and then inclined at an angle to effect the desired direction of the aeroplane. Immediately the foot pressure on the pedal 51 is withdrawn, the coiled spring 44 will force the shaft 33 and rudder 35 connected thereto by the link 32 back to normal position 120 illustrated in full lines in Fig. 1.

The aviator will employ only one hand and one foot in guiding the course of the aeroplane and will have one hand free to work the machine gun 81. From his seat 4, the aviator will be able to look out 125

through the glass windows 90 of the framework 71 and also have opportunity to look along the sights 85 and 86 of the machine gun 81, whereby to aim the same.

5 The rock frame 8 will hold the aviator and gun 81 in horizontal position with reference to the earth, irrespective of the tilt of the aeroplane.

Fig. 11 shows a modified manner of actuating the rudder 91 of the aeroplane. The rudder 91 is here joined to the casing —1— by a ball and socket joint 92, whereby the rudder can be swung at various angles to the casing —1—, to direct the course of the aeroplane. The rudder 91 has four planes disposed at right angles to each other. A cord 97 or cable is attached to each plane near its outer edge and passed along to the interior of the aeroplane where it is finally secured to a disk 93. The disk 93 is mounted by a ball and socket joint 94 to the partition 95 and has a handle 96. The aeroplane can be directed in its course by moving the handle 96 in the given direction, whereby the rudder 91 will be actuated at an angle corresponding to the direction of movement of the handle 96 and of the course desired.

Fig. 12 shows certain mechanism for actuating a divided plane designated 100—100, whereby to guide the direction of the aeroplane. The mechanism for actuating the planes 100 will effect a quicker result than that effected by the rudder. The planes are keyed to turn with the shafts 101—101, which are mounted to revolve with the spur gears 102—102 in mesh with the rack 103. A shaft 104 is formed integral with the rack 103 and is mounted to slide in a sleeve 105 of a bracket 106 secured to the casing —1—. The rack 103 is moved back and forth by a lever handle 107 having an elongated recess for the play of a pin 108 mounted in the bifurcated end of the rack 103. The lever handle 107 is fulcrumed at 110 to a bracket 111 attached to the casing —1—.

Although the wheels of the aeroplane are not here shown, the same may be mounted upon a movable frame that can be drawn up within the casing —1— when the aeroplane is in the air, whereby to eliminate any resistance thereof by the air and then dropped down again when the aeroplane is about to alight. The movable frame can be controlled by a lever located near the aviator's seat 4.

A bolt or shaft may be inserted through

the holes 115 in the pendulum member 53 and the forward partition 55, whereby to hold the rock frame stationary, or so as to tilt with the motion of the casing —1—.

Having thus described our invention what we claim as new and desire to secure by Letters Patent is:

1. In an aeroplane, a rudder adapted to revolve, a train of gears for revolving said rudder, a crank handle for controlling the movement of said gears, a longitudinally movable shaft for tilting said rudder, a pedal for actuating said shaft, and a spring for yieldingly holding said shaft in given position, whereby to return the rudder to its original position.

2. In an aeroplane, a rudder adapted to move in two planes, a train of gears for turning said rudder in one plane, a spring pressed longitudinally movable shaft for tilting said rudder in another plane, and a handle and a pedal for controlling the movements of said rudder, whereby to guide the aeroplane.

3. In an aeroplane, a casing having an aperture for the entrance and exit of a pilot, a cap disposed at the end of said casing, a rudder fulcrumed to said cap, a longitudinally movable shaft, whereby said rudder can be tilted in one plane, a hollow tube, whereby said rudder can be revolved in still another plane, to direct the course of the aeroplane, and a pedal for actuating said shaft.

4. In an aeroplane, a rudder adapted to revolve, a rotary cap adapted to support said rudder in a pivotal manner, a spring actuated shaft for turning said rudder upon its pivot, a tube connected with said cap, and gears for revolving said tube and rudder, whereby to aid in directing the course of the aeroplane.

5. In an aeroplane, a rudder adapted to revolve, a rotary cap adapted to support said rudder in a pivotal manner, a spring actuated shaft for turning said rudder upon its pivot, a tube connected with said cap, gears connected with said tube, a pivoted member adapted to actuate said shaft, whereby to tilt the rudder upon its pivot, and a handle for turning said gears, whereby to turn said rudder, to aid in directing the course of the aeroplane.

In testimony whereof we have affixed our signatures.

JAMES S. JOHNSTON.
MILLARD L. JOHNSTON.
